UNITED STATES PATENT OFFICE

2,408,287

ELECTRON MICROSCOPE

Charles H. Bachman, Scotia, N. Y., assignor to
 General Electric Company, a corporation of
 New York

Application February 1, 1944, Serial No. 520,610

5 Claims. (Cl. 250—49.5)

1

The present invention relates to electron optical apparatus particularly adapted for the microscopic examination of electron pervious objects. It is an object of the invention to provide a new and improved fluorescent screen for an electron microscope.

It is known that objects may be microscopically examined by the rays of an electron beam which transradiates the object, the beam passing through the object and in this passage being provided with the characteristics thereof. Such an electron beam may be refracted by appropriately conditioned fields and the beam may be impinged upon a fluorescent screen, an image being constructed on the screen in accordance with the characteristics given to the beam in its passage through the object. It has been observed that there are two fundamental limitations in the use of fluorescent screen in electron microscopy where an electron beam is impinged upon and passes through the screen. These limitations are the size of the phosphor or fluorescent particles and the physical thickness of the screen. The limitations of course are of consequence only when optical magnification of an image on the screen is desired. In this case, as the image on a fluorescent screen is enlarged to magnifications of the order of 25 diameters, the thickness of the screen, that is, the number of layers of phosphor or fluorescent particles causes the edges of the image to become blurred or fuzzy. On the other hand, the size of the individual phosphor particles can be so controlled that this factor does not enter as a limitation of magnification until enlargements of the order of several hundred diameters are reached. Improved magnification may be attained, therefore, if a sufficiently thin fluorescent screen, preferably consisting of a single layer of fluorescent particles, may be constructed satisfactorily without the occurrence of tiny holes due to incomplete coverage of a screen surface deleteriously affecting satisfactory imaging of the magnified object.

It is an object of my invention to provide improved means by which very thin fluorescent screens may be successfully employed in electron optical studies of objects.

An important feature of the invention consists in an apparatus arrangement by which thin fluorescent screens used in electron optical studies are moved laterally to effect a smoothing out of all irregularities in the screen structure and with sufficient frequency to eliminate visual effects.

The features of the invention which I desire to protect herein are pointed out with particularity

2

in the appended claims. The invention itself together with further objects and advantages thereof may best be understood by reference to the following description taken in connection with the accompanying drawing in which Fig. 1 represents diagrammatically an end section of an electron optical system employing my invention and Fig. 2 is a cross-sectional view showing the fluorescent screen supporting arrangement of the invention.

Referring to Figs. 1 and 2 jointly, there is shown an electron microscope comprising an elongated vacuum-tight container 10 of a tubular metal construction. At one end of the container, 15 there is provided a glass insulator 11 which serves to support an electron source in the form of a filamentary cathode 12. The cathode 12 is surrounded by a tubular metal member 13 which confines the emitted electrons to a narrow beam and is cooperatively positioned with respect to an apertured electrode 14 which is in contact with the metal envelope part 10. The opposite end of the envelope 10 is sealed by a glass window 15. A fluorescent viewing screen 16 is positioned with- 20 in the tube 10 in front of the window 15.

In the normal use of the apparatus, the envelope 10 and the apertured electrode 14 are maintained at ground potential and the cathode 12 is maintained at a high negative potential, for example, being connected to a potential source represented by the battery 17 so that electrons emitted from the cathode are projected axially of the container with the object of producing a visible image on the fluorescent screen 16.

Between the cathode 12 and the image-reproducing screen 16 there is provided object supporting means indicated generally at 18. In the intended use of the apparatus, this means is to be employed as a support for an object to be transradiated by an electron beam, the beam being passed-through the object and in the passage assuming the characteristics of the object. A supporting structure may be provided in connection with the object supporting means 19 and may likewise employ appropriate clamps or other means (not shown) for holding an object with its surface in exposed position to the electron beam 20.

In order that the electron beam, after modification in accordance with the structural character of the object under investigation as the beam transradiates the object, may be caused to provide an enlarged visible image of the object in accordance with the intended use of the microscope, the beam 20, after passing through the

object, is caused to pass through an electron lens system of known character. In the drawing, the lens system is illustrated as of the electrostatic type, although a lens system of the magnetic type may be employed. The lens system comprises a series of three diaphragms, numbered 22-24, inclusive. The diaphragms 22 and 24 are maintained at the potential of the casing 10, that is, at ground potential and the intermediate diaphragm 23 may be insulatingly supported and is biased to cathode potential through a connection 25 which is brought into the microscope enclosure through an insulating bushing 26. Because of the resultant difference in potential between the diaphragm 23 and diaphragms 22 and 24, lens fields are established between these diaphragms which have the effect of refracting the electron beam in a manner analogous to the refraction of a light beam by an optical lens. Additional lens fields may be employed in the electron microscope where so desired.

Means are provided for optical magnification of the image formed on the fluorescent screen 16 and this means is represented conventionally as an optical lens 29 through which the beam of visible radiation 23, projected through window 15 from fluorescent screen 16, is caused to pass.

The fluorescent screen 16 shown in plan view in Fig. 2 comprises a frame member 30 which may be either circular or rectangular in shape and which supports a transparent window 31 upon which is deposited a thin coating of a suitable fluorescent material 32. Preferably, the coating 32 consists of a minimum number of layers of small particles of a suitable phosphor. The frame 30 is suspended within member 10 by means of a set of spring members 33 which provide a good conductive connection between screen 16 and tube 10. To one edge of the frame 30, there is attached a rod member 35 which extends through an opening 36 in tube 10 and passes through a bellows device 37, the bellows 37 providing a seal across opening 36. The member 35 has a portion extending exteriorly of the bellows 37 by which motion may be imparted to screen 16 to produce lateral movement of this screen.

In order to prevent any motion imparted to screen 16 by activating rod 35 from producing axial motion of the screen to affect either the electronic or optical focus, a plurality of guide members 39 are attached to the inner surface of container 10. The guide members 39 may be provided with slots or fingers at one of their ends and the screen 16 may be restrained by these fingers from axial movement and yet permitted to move in a plane perpendicular to the axis of the container 10.

By the screen supporting arrangement described, the screen 16 may be moved laterally and the effect of any kind of screen irregularities, such as holes, dirt specks, and similar defects in the phosphor coating on screen 16 which would normally produce distortion in optically enlarged images on the fluorescent screen 16 is eliminated. Since the electron beam 20 always bombards the same points in space, as the screen 16 is shifted in a plane perpendicular to the beam, the effect of smoothing out all the irregularities of the above-mentioned type in the screen structure is obtained. So long as the motion is confined to a lateral direction and there is not sufficient axial motion to affect either electronic or optical focus, no ill effects in the re-

production of the electron image are encountered.

To eliminate any possible visual defects in the reproduction of the electron image, as the screen 16 is moved laterally, the frequency of motion of screen 16 of course must be greater than the flicker frequency of the human eye. To this end, a frequency of 20 cycles per second or greater should be employed in movement of rod 35. Such vibration of the rod 35 may be obtained by means of an electrical coil 40 energized from a suitable source of alternating voltage 41 through a control switch 42. An armature 43 may be provided at the lower end of rod 36 to be vibrated by coil 40.

When the lens system 29 is replaced by a camera for photographing the image produced on screen 16, the need for eliminating flicker effect is no longer present so that at such times the frequency of vibration of screen 16 may be reduced and the screen may be moved manually during the exposure time.

By the present invention, in an electron microscope of the type described above, a fluorescent screen may be employed which is made up of a single layer of fluorescent particles. Such a screen usually is not suitable for electron microscopic examinations, since the coverage of the screen under such conditions is only about 60% complete. In the normal microscope, therefore, more effective coverage of the screen surface is obtained by adding additional layers of fluorescent material. In a microscope, however, in which lateral shaking of the screen is provided, a single layer of fluorescent particles may be employed and the shaking produces the effect of a completely covered very thin screen having reduced light output because of the decreased number of fluorescent particles.

While I have shown a particular embodiment of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. The combination, in an electron microscope, of a viewing screen coated with a thin layer of fluorescent material and means for producing lateral motion of said screen to reduce blurring of images produced on said screen.
2. An electron microscope comprising an evacuated container having a fluorescent screen positioned therein, means for projecting a beam of electrons upon said screen, means for supporting an object to be examined in the path of said beam, and means for vibrating said screen in a plane substantially transverse to said beam to reduce blurring of the image of said object produced on said screen.
3. An electron microscope system comprising an evacuated container having a transparent wall, a fluorescent screen supported within said container in front of said wall, means for projecting an electron beam upon said screen, means for supporting an object to be examined in the path of said beam whereby said beam produces an enlarged image of said object upon said screen, means external of said container for producing optical enlargement of the image on said screen, and means for vibrating said screen in a plane substantially transverse to said beam to reduce blurring of said enlarged image due to

5

non-uniform distribution of fluorescent particles on said screen.

4. In combination, a viewing screen coated with a thin layer of fluorescent particles, means for producing an image to be viewed on said screen, optical means for enlarging said image to a degree such that irregularities in the deposition of said particles on said screen produce objectionable blurring of said enlarged image, and means for vibrating said screen in a plane transverse to the optical axis of said optical means to reduce said blurring.

5

5. The combination, in an electron microscope having a vacuum-tight container, of a fluorescent screen resiliently supported within said container, means for projecting an electron beam on said screen to produce an image thereon, means for optically enlarging said image, and means for vibrating said screen in a plane transverse to said beam to reduce blurring in said enlarged image.

CHARLES H. BACHMAN.
